No. 1353

Elimir J. Ney of Lowell Mass
Assignor to
Lowell Manuf Co
Letter Patent No 1353 Dated Dec 18th 1860

The schedule referred to in the Letter Patent and writing part of the same,

To all whom it may concern:

Be it known that I, Elimir J. Ney, of Lowell, in the County of Middlesex and State of Massachusetts, have originated and designed a new pattern for carpets or other fabrics, of which the following is a full, clear, and exact description, reference being had to the accompanying drawings, writing part of this specification.

The design which is worked from one large diamond each of which is divided into four smaller ones by bands running at right angles with each other throughout the design. The small diamonds of the corners are composed of small regular work, and those of the center each enclose a small group of leaves and flowers. The design is so full, different portions of the design may be raised to suit the taste and wish of the manufacturer.

That I claim as my invention and desire to secure by Letter Patent, is:-

The design or pattern for carpets or other fabrics herein set forth.
